UNITED STATES PATENT OFFICE.

WILHELM WEBER, OF HAYINGEN, GERMANY.

MEANS FOR TAMPING BORE-HOLES CHARGED WITH BLASTING COMPOUNDS.

1,218,140.

Specification of Letters Patent.

Patented Mar. 6, 1917.

Application filed October 1, 1915. Serial No. 53,480.

To all whom it may concern:

Be it known that I, WILHELM WEBER, a subject of the German Emperor, residing at Hayingen, Lorraine, Germany, have invented 5 new and useful Improvements in Means for Tamping Bore-Holes Charged with Blasting Compounds, of which the following is a specification:

This invention relates to means for tamping bore-holes charged with a blasting compound, and more particularly to means for tamping blasting charges which are based on the action of liquid air.

In another application for a patent I have 15 described blasting cartridges consisting of a combustible metallic powder, an absorptive substance for liquid air, and a primer. These compounds may either be introduced directly into a chamber-like enlargement of 20 the bore-hole, whereafter the liquid air is added by pouring same into the absorptive mass; or the blasting charge is placed into a cartridge and saturated with liquid air either prior to or after, introduction of the 25 cartridge into the bore-hole, which for the reception of the cartridge need not be provided with a chamber-like enlargement. In either case the tamping is put on at last. On contact of the saturated absorbent, or the 30 saturated blasting cartridge, with the walls of the bore-hole a portion of the liquid air quickly evaporates on account of the heat received from the walls of the bore-hole, and the vapors developing may produce the re- 35 sult that the tamping is expelled from the bore-hole. To avoid such an expulsion of the tamping it has been a usual practice hitherto to leave a small passage in the tamping through which the vapors could es- 40 cape. However, it may occur that the passage provided for the escape of the vapors is either insufficient to permit all vapors to escape, or else, it is made too large so that the necessary explosive effect will not be ob- 45 tained.

It is the object of my present invention to provide improved means for tamping bore-holes which improved means are adapted to permit the vapors of the liquid air to escape 50 during the action of putting the tamping on but successfully prevent an expulsion of the tamping should an increased pressure be produced within the blasting charge. In tamping the bore-hole I first place the usual 55 tamping material loosely on top of the blasting charge, or the blasting cartridge, thus

allowing the vapors to escape through the space left between the cartridge and the tamping on the one hand and the wall of the bore-hole on the other. Upon the tamping I 60 place a stopper provided with novel means for locking same within the bore-hole; the stopper may be made of wood or the like suitable material, and by means of the stopper the tamping may finally be pressed home 65 to any desirable degree.

The accompanying drawings illustrate, by way of example, a tamping in accordance with my invention, for an explosive charge prepared within a bore-hole. In the drawings Figure 1 represents a longitudinal section through a bore-hole with the novel tamping in place, and Fig. 2 is a cross section taken on the line A—B in Fig. 1.

Referring to the drawings, *a* represents a bore-hole, *b* a blasting charge therein, *c* tamping material placed on top of the blasting charge, and *d* a stopper made of any suitable material and provided with plate springs *g* of steel, the plate springs having 80 their ends bent outwardly toward the mouth of the bore-hole, so as to engage the wall of the bore-hole. At *d'* the stopper is shown in dotted lines at the mouth of the bore-hole while being passed down the latter. The 85 wires leading to the primer for setting the charge are indicated at *e*. The stopper is of a smaller diameter than the bore-hole, while the length of each spring *g* exceeds the diameter of the bore-hole. One plate 90 spring *g* may be used, or a plurality of same. When using two springs I prefer to dispose them crosswise as shown, and to fasten them on the stopper by means of a screw. Other suitable fastening means may be employed. 95

As will be seen on reference to the drawings the ends of the springs have become bent round somewhat toward the mouth of the bore-hole; thus, when through liquid air evaporating a pressure is produced that acts 100 on the stopper *d* the ends of the springs become engaged with the wall of the bore-hole in such a way as to lock the stopper *d* and to prevent an expulsion of the stopper.

I wish it to be understood that my invention is not limited to the special constructions shown in the drawings; various modifications may be made without departing from the essence of my invention.

What I claim is:—

1. In means for tamping bore-holes, a blasting cartridge, a superposed stopper of

smaller diameter than the bore-hole to form a clearance therebetween, a plate spring on said stopper the length of said plate spring exceeding the diameter of the bore-hole, 5 whereby said stopper is held in the bore-hole against expulsion owing to the ends of said plate spring engaging the wall of the bore-hole.

2. In means for tamping bore-holes, a 10 blasting cartridge, a superposed stopper adapted to be introduced loosely into the bore-hole to form a clearance therebetween, and plate springs on said stopper, each of which plate springs exceeding in length the 15 diameter of the bore-hole.

3. The combination with a tamping material for tamping bore-holes, of a stopper of smaller diameter than the bore-hole to form a clearance therebetween, said stopper 20 being adapted to be placed on top of the tamping material, and plate springs exceeding in length the diameter of the bore-hole, said springs being fastened to said stopper so as to become bent round at their ends

while said stopper is being inserted into the 25 bore-hole.

4. The combination of a blasting charge with tamping material placed on top of said blasting charge, a stopper placed on top of said tamping material, and plate springs on 30 said stopper having their ends bent toward the mouth of the bore-hole and engaging the wall of the bore-hole so as to prevent the tamping from being expelled.

5. In combination, a blasting charge containing liquid air, a tamping of smaller diameter than the bore-hole, a stopper adapted to fit loosely into the bore-hole to form a clearance therebetween, and plate springs on 35 said stopper, said plate springs being adapted to engage the wall on the bore-hole so as to offer resistance against any expelling force acting on said stopper from within said blasting charge.

WILHELM WEBER.
